HIGHWAY GUARD

Theodore R. Weber, Latrobe, Pa., assignor to
 American Locomotive Company, New York,
 N. Y., a corporation of New York

Application May 4, 1939, Serial No. 271,666

7 Claims. (Cl. 256—13.1)

This invention relates to flexible cable highway guards, and more particularly to standards for supporting the cables thereof.

An object of the invention is to provide an improved highway guard standard employing coil springs for absorbing the forces transmitted to the standard.

A further object is to provide such a standard in which the coil springs are conical, affording for each spring, a large base area, providing greater stability and preventing unseating of the spring during collision of a motor vehicle with the guard.

A further object is to provide a standard employing conical springs and utilizing the spring characteristics that the large coils compress under ordinary collision forces and the small coils compress under forces of large magnitude, thereby providing a highway guard capable of properly cushioning collision forces of various magnitudes.

A further object is to employ a spring, where desired, which will take a permanent set under excessive impacts, preventing recovery of the spring and therefore absorbing a large part of the force of the impact through plastic torsional deformation.

Other and further objects of and advantages achieved by the present invention will be apparent from the following description of an approved embodiment thereof.

Referring to the drawing forming a part of this application, Figure 1, is a side elevation of a portion of a highway guard, showing one standard completely assembled as when in use, the highway guard posts and cables being indicated fragmentally in dot and dash lines; Fig. 2 is a front view of the structure shown in Fig. 1; and Fig. 3 is a section on the line III—III of Fig. 1, parts being shown in full.

A highway guard is a safety fence which is placed along a road at dangerous spots to prevent motor vehicles from leaving the road. It should be a flexible fence which will minimize the danger to vehicles colliding therewith and which will have sufficient strength to withstand ordinary collisions without injury to the fence itself. Highway guards formed of spaced flexible cables supported by standards of various kinds are well known, and most of them which are in use today are objectionable to some extent because of the inability of the standards to stand up under the forces applied to them by colliding vehicles, or, on the other hand, if strong enough,

because of their rigidity which detracts from their safety value.

The present invention involves a novel standard employing coil springs for resisting the aforesaid forces in such a manner as to provide a shock-absorbing standard which does not have the aforesaid undesirable characteristics.

A highway guard consists of a row of standards connected by cables. In the drawing only one standard is shown as all standards of the highway guard are ordinarily similar. The highway guard standard, indicated by the numeral 1, shown in the drawing comprises a post 2, which may be made of wood, concrete, iron or other suitable material and which may be of various shapes, but preferably, as shown in the drawing, has a flat vertical front face 3 or at least flat vertical portions which will provide spring seats. The post, when in use, has a portion imbedded in the ground and a portion extending upward for supporting the cables. The posts have orifices 4 for receiving attaching means later to be more fully described.

In Figs. 1 and 2 a standard for supporting three cables is shown, and the invention is described in connection with such a standard, but it will be understood that the standard may support only one cable, or more cables, as is desired. The cables, indicated by the letter a, engage a plate 5, which is of elongated cup or trough shape, the elongation extending in a vertical direction. The plate comprises an outer wall 6 having a flat outer face turned outward away from the post, and side walls or flanges 7 extending toward the face 3 at an inclined angle thereto, similar to the angle of conical springs 8 disposed between the plate 5 and the post 2.

A conical spring 8 is disposed between the face 3 and the plate 5 at each end of the plate. These springs may be of a conventional type which will completely recover under each deflection regardless of the force which compresses them, or they may be novel springs which will increase the advantages of the highway guard. That is to say, the conical springs may be springs which will deflect and recover in the ordinary manner under ordinary impacts, but which will, when the highway guard receives a heavy impact, take a permanent set. Thus, if a vehicle collides with the highway guard with a force which would ordinarily be dangerous to the human occupants in the vehicle, the spring will be compressed thereunder beyond the limit of its flexibility and there will be a plastic torsional deformation of the spring which will prevent its complete recov-

ery from the deflection. This deformation absorbs a large part of the force of the impact and offers a constant resistance to the impact, dissipating the force, preventing a corresponding force being applied to the vehicle by the spring, and cushioning the force finally applied to the post. This feature of the invention is not confined to conical springs but in fact may be employed in any suitable type of spring and in other types of guard rails.

The larger base of each spring, whether of the conventional or novel type of conical formation, seats upon the face 3 and the smaller outer end of each spring seats upon the inner face of the wall 6 between the side walls 7. The side walls 7 stiffen and strengthen the plate and serve as retaining walls to keep the spring from moving in a direction theretoward. The plate 5 serves to tie the two springs together. The coils of each spring are large enough relative to the size of the bar from which they are made to provide a conical opening through the center of the spring so that means later to be described can extend through the spring.

25 The plate 5, at its portions adjacent the outer ends of the springs and disposed over the openings therein, contains slots 9. An open link 10 extends through each slot 9, providing parts projecting from each side of the wall 6. The outer end portion of each link forms a short hook 11 and the inner end portion forms a long hook 12. Each of the hooks 11 and 12 have a free leg together forming the side of the link which is open, and the adjacent ends of the legs are disposed between the wall 6 and the post 2 and are separated by a space 13. When the links 10 are assembled with the cables a, which is preferably accomplished by passing the cable a through the space 13, the cables are moved into the hooks 11, 30 which support them, when the standard is completely assembled, in spaced relation to the post 2 and in engagement with the flat face of the plate 5, the links 10 extending inward part way through the center of the spring.

45 An attaching means, which in the present instance is a bolt 14 having a hook 15 at one end, extends at its hooked end into the conical opening of each spring 8 from the inner end thereof, each hook 15 gripping the adjacent hook 12, 50 forming a flexible connection consisting of a link 10 and a bolt 14. The other end of each bolt 14 passes through the adjacent orifice 4 and is secured to the post by a nut 16 and washer 17. The end of the leg 18 of each hook 15 abuts 55 against the face 3, thereby, with the adjacent nut 16, preventing movement of its bolt 14 in the post 2.

The springs 8 are compressed, by the tightening of the nut 16, to a predetermined extent according to the minimum force which the designer of the highway guard wishes to cushion. The compression of the springs is also sufficient to force the plate 5 away from the post under ordinary conditions so that the highway guard presents a 65 normally rigid fence which only gives under predetermined collision forces.

The center cable a is secured to the plate 5 by a yoke 19 which has a threaded leg 20. Holes 21 are formed in the central portion of the plate 5 and the legs of the yoke 19 extend through these holes. The holes 21 may be replaced by slots, if desired, and likewise each slot 9 may be replaced by a pair of holes. The yoke is secured to the plate by a nut 22 threaded on the leg 20. The 70 75 cables hold the plate 5 in its normal position,

thereby serving to hold all the members of the highway guard together. As shown in Fig. 1, the free leg of the hook 12 is bent inward toward the opposite side of the link 10 sufficiently to prevent the link 10 from slipping off the bolt 14 when the link moves toward the post during movement of the cables and plate 5 toward the post.

The cables a stand out from the plate 5 and only the relatively small diameter of the hook 11 and yoke 19 extends over the cable. Thus the 10 cables are practically unobstructed to substantially provide a continuous sliding surface for a colliding vehicle which will tend to deflect the force with which the vehicle hits the highway guard.

As before mentioned, it may be desired that the 15 standard support only one cable, and in that event the plate 5 may be supported by two springs, as shown, or, if desired, only one spring need be employed. In the latter case the plate 5 will be circular or square instead of elongated as 20 shown, and in other details the construction would be similar to the construction already described. If two cables are employed, the middle cable and yoke alone would be eliminated. More 25 springs, with their attaching means, and more 30 yokes may be added if it is desired to employ additional cables. Cylindrical helical springs may also be employed instead of conical springs, where the additional desirable features of the conical springs are not required.

35 The operation of the highway guard, when a motor vehicle collides with it, is as follows: If the force is fairly light, the flexibility of the cables alone may stop the vehicle safely, or, if such a force is applied directly to the plate 5, 40 either one or both springs will be compressed to some extent and the force cushioned. Under forces which do not need to be cushioned, the normal compression of the springs allows the highway guard to stand up against the forces as 45 a normally rigid fence. If the center cable alone is hit, both springs resist the force, and if either of the outermost cables is hit alone, one spring mainly will resist the force, affording approximately 50% of the total resistance available.

50 If the collision is severe and a force of large magnitude is applied to the cables, the cables will themselves cushion the force to a certain extent. This is assisted by the sidewise movement of the plate 5 due to the flexibility of the springs and 55 the link connections. Although under very severe impacts the cables can move in the hooks 11 and yokes 19 of the various standards against the frictional resistance of their engagement thereby. Furthermore they are usually twisted 60 cables of many strands, flexible longitudinally to a certain extent, and will yield under severe collision forces. The excess force will be transmitted to the adjacent standards and also to successive standards dependent upon the magnitude of the 65 force, for in such instances the cables act to distribute the force of the collision over a number of standards.

65 Any sufficient force applied to a plate 5, whether it is transmitted from a cable or whether the plate 5 is collided with directly, will move the plate 5 toward the post 2 against the resistance of the springs, and the shock of the force will be broken and partly dissipated before it is transmitted to the post 2. Thus when the highway 70 guard stops the vehicle, considerable of the collision force will have been cushioned. Therefore little damage will ordinarily result to the vehicle or to the highway guard.

75 Where the deformable springs are employed 75

and where the impact as aforesaid, is a severe one which would be dangerous to human life, the springs will be compressed until the limit of their flexibility is reached, which is before the solid height of the spring is reached, and during further compression the springs will take a permanent set, as aforesaid, affording additional cushioning of the force by the plastic torsional deformation of the spring. Of course, springs which are permanently set by severe collisions must be replaced, but this replacement is relatively inconsequential as compared to the protection afforded, for the force that is used up in setting the spring would otherwise be received by the vehicle and the occupants thereof. A simple deformable spring which is well adapted for the above described use in a highway guard, is a spring which has been tempered but has not been set after being tempered. It is therefore ready to be set by the first force which compresses it beyond a predetermined extent.

Where conical springs are employed, the spring will maintain its seat upon the post due to the large base area of the spring even when the force is applied against the side of the plate 5, and will therefore remain in an operative shock-cushioning position until the colliding vehicle is stopped. A force of sufficient magnitude to move one of the plates toward the adjacent face 3 will cause the large coils of the conical springs to compress first and if the force is not of a large magnitude, these coils alone may act to cushion the force, but where the force is severe, the small stiffer coils of the conical springs will also be compressed, resisting the added force.

Thus a highway guard is provided which will act to cushion light forces and to cushion heavy forces, which is an improved feature absent in highway guards now commonly employed.

While there has been hereinbefore described an approved embodiment of this invention, it will be understood that many and various changes and modifications in form, arrangement of parts and details of construction thereof may be made without departing from the spirit of the invention and that all such changes and modifications as fall within the scope of the appended claims are contemplated as a part of this invention.

The invention claimed and desired to be secured by Letters Patent is:

1. A highway guard standard for supporting a highway guard cable comprising a post having a face for facing the highway; a helical spring seated on said face for flexing, extending outward therefrom; a plate seated on the outer end of said helical spring in opposed spaced relation with said face, said plate having an outer face adapted to engage said cable; and a link connecting means for securing said cable to said plate, said means extending through said plate and said spring and secured in said post, securing said plate, spring and post together, thereby supporting said cable by said standard, whereby forces applied to said cable or plate will be resisted by said spring and said spring will yield under forces beyond a predetermined magnitude to cushion such forces.

2. A highway guard standard for supporting a highway guard cable comprising a post having a face for facing the highway; a helical spring seated on said face for flexing, extending outward therefrom; a plate seated on the outer end of said helical spring in opposed spaced relation with said face, said plate having an outer face adapted to engage said cable; and link connecting means

comprising a link extending through said plate adapted to engage said cable and to secure said cable to said plate, said means passing through said spring with said link passing only partly through said spring to provide a flexible connection within said spring, said means being secured to said post, thereby securing said cable, plate and spring to said post, said flexible connection permitting said cable, plate and link to move toward said post when forces beyond a predetermined magnitude are applied to said cable or plate, whereby said forces will be yieldingly resisted by said spring.

3. A highway guard standard for supporting a highway guard cable comprising a post having a face for facing the highway; a helical spring seated on said face for flexing, extending outward therefrom; a plate seated on the outer end of said helical spring in opposed spaced relation with said face, said plate having an outer face adapted to engage said cable; and link connecting means comprising an open link extending through said plate adapted to receive said cable through the opening in said link and to secure said cable to said plate, said means passing through said spring with said link passing only partly through said spring to provide a flexible connection within said spring, said means being secured to said post, thereby securing said cable, plate and spring to said post, said flexible connection permitting said cable, plate and link to move toward said post when forces beyond a predetermined magnitude are applied to said cable or plate, whereby said forces will be yieldingly resisted by said spring.

4. A highway guard standard for supporting a highway guard cable comprising a post having a face for facing the highway; a helical spring seated on said face for flexing, extending outward therefrom; a plate seated on the outer end of said helical spring in opposed spaced relation with said face, said plate having an outer face adapted to engage said cable; and link connecting means comprising a link extending through said plate adapted to engage said cable and to secure said cable to said plate, a bolt having a loop connected to said link; a leg of said loop abutting said post face, said bolt passing through said post, and a nut securing said bolt to said post, said connecting means passing through said spring with said link passing only partly through said spring to provide a flexible connection within said spring, said connecting means securing said cable, plate and spring to said post, said flexible connection permitting said cable, plate and link to move toward said post when said forces beyond a predetermined magnitude are applied to said cable or plate, whereby said forces will be yieldingly resisted by said spring.

5. A highway guard standard for supporting a highway guard cables comprising a post having a face for facing the highway; a pair of vertically-spaced helical springs seated on said face for flexing, extending outward therefrom; a plate spanning said springs, seated on the outer ends thereof in opposed spaced relation with said face, and having peripheral flanges directed toward said face, said plate having an outer face adapted to engage said cables in vertical spaced relation; and means for securing said cables, plate and springs to said post whereby forces applied to said cables or plate will be resisted by said springs and said springs will yield under forces beyond a predetermined magnitude to cushion such forces.

6. A highway guard standard for supporting a highway guard cable comprising a post having a face for facing the highway; a tempered helical compression spring having its inner end seated on said face for flexing and extending outward therefrom; means supported by said spring at its outer end for supporting said cable in opposed spaced relation with said face; and a link connecting means for securing said cable to said cable-supporting means, said connecting means extending through said spring and secured to said post, thereby securing said cable-supporting means, spring and post together for supporting said cable by said standard whereby forces applied to said cable or said cable-supporting means will be resisted by said spring and said spring will yield to cushion said forces.
7. A highway guard standard for supporting highway guard cables comprising a post having a face for facing the highway; a pair of

vertically-spaced helical compression springs having their inner ends seated on said face for flexing and extending outward therefrom; a plate spanning the space between said springs and seated on the outer ends thereof in opposed spaced relation with said face, tying said springs together for unitary action of said springs and plate, said plate having an outer face adapted to engage said cables one opposite each said spring; and link connecting means at each spring 10 for securing said cables to said plate, each said means extending through said plate and through said spring adjacent thereto and secured in said post, thereby securing said plate, springs and post together for supporting said cables by said standard, whereby forces applied to said cables or plate will be resisted by said springs and said springs will yield under forces beyond a predetermined magnitude to cushion such forces.
